(57) **CLAIM**

The ornamental design for a bathroom sink faucet, as shown and described.

DESCRIPTION

FIG. 1 is a front elevation view of a bathroom sink faucet showing the new design;

FIG. 2 is a back elevation view thereof;

FIG. 3 is a left-side view thereof;

FIG. 4 is a right-side view thereof;

FIG. 5 is a top plan view thereof;

FIG. 6 is a bottom plan view thereof;

FIG. 7 is a perspective view thereof; and,

FIG. 8 is another perspective view thereof; and,

FIG. 9 is a perspective view of the bathroom sink faucet as it would be positioned during use.

The broken lines of FIG. 9 depicting a sink represent environmental structure that forms no part of the claimed design. The remainder of the broken lines depict portions of the bathroom sink faucet that form no part of the claimed design.

1 Claim, 9 Drawing Sheets
